E. B. FINLAYSON

CONTAINER

Filed June 3, 1921

Inventor
Estelle B. Finlayson

By *James F. McLean*
her Attorney

UNITED STATES PATENT OFFICE.

ESTELLE B. FINLAYSON, OF OSSINING, NEW YORK.

CONTAINER.

Application filed June 3, 1921. Serial No. 474,636.

To all whom it may concern:

Be it known that ESTELLE B. FINLAYSON, a citizen of the United States, residing in Ossining, county of Westchester, and State 5 of New York, has invented certain new and useful Improvements in Containers, of which the following is a full, clear, and exact specification.

My invention relates to containers and 10 refers particularly to containers suitable for employment with face powders.

Face powders are usually applied by means of powder puffs, it therefore being necessary to transfer the powder from its 15 container to the powder puff before use.

Face powders are usually sold in containers having sifting tops composed of a perforated member carrying means whereby the perforations may be opened or closed.

20 In order to transfer the powder from the container to the puff, the holes are opened and the powder sifted therethrough upon the puff. On account of the fineness and lightness of the powder, a very considerable 25 amount of it falls elsewhere than upon the puff, thus frequently injuring dress fabrics and causing considerable trouble, and, at times, expense in removing it therefrom. This wastage of powder is also the cause of 30 loss of powder with its consequent expense.

The present employed containers also possess the objection that frequently the sifting closure is not absolutely tight, or becomes open when not in use, thus causing a 35 loss of powder coupled with the inconvenience of the powder injuring other materials.

40 In the accompanying drawings, illustrating one form of the device of my invention, similar parts are designated by similar numerals.

Figure 1 is a vertical cross-section of one form of my device.

45 Figure 2 is a top plan of Figure 1, partly broken away.

The particular form of the device of my invention, shown in the accompanying drawings, comprises a container having the 50 side 10, the bottom 11 and the top 12, the container being separated into two chambers, an upper chamber 13 and a lower chamber 14 by the division wall 15. Centrally positioned within the division wall 15 is a hole 16, covered by the powder sifter

17, the holes 18, 18 of which are capable of being closed by the revoluble top 19.

The top 12 of the container has an opening 20, capable of being closed by the lid 21, which is hinged at 22 and has a closure 60 catch 23 to prevent its accidental opening.

The dot and dash lines 21', 23' show the lid 21, 23 in open position.

The bottom 11 has a filling hole 24, capable of being closed by the closure cap 25. 65

The operation of the device is as follows:—

Toilet powder 26 is introduced into the chamber 14 through the opening 24, which is closed by means of the cap 25. The cover 70 21 is closed and the holes 18, 18 opened. By reversing the container and shaking slightly, some of the powder 26 will escape through the holes 18, 18 into the chamber 13 and by bringing the container to its normal position, this powder will settle upon the upper 75 face of the dividing wall 15. The cover 21 is then opened, the holes 18, 18 are closed by means of the revoluble top 19, and the powder puff 27 inserted therethrough into 80 the chamber 13 and thus rests upon the powder carried by the wall 15. The cover 21 may then be closed.

It is evident that the powder in the chamber 13 will adhere to the powder puff 27 85 and, when it is desired to use it, it may be removed through the opening 20. Before replacing the powder puff, the above described operation is repeated to convey some of the powder from the chamber 14 into the 90 chamber 13.

It will thus be seen that by means of my device, powder may be applied to a powder puff without any danger of any of it sifting upon other objects, thus presenting an 95 economic and cleanly means of accomplishing the result.

It is further evident that the annoyance of the sifting of the powder, when the container is not in use, is overcome, because, if 100 any powder should escape through the sifter, it will be retained in the upper chamber 13.

Sifting devices other than that shown may be employed, as the one described is 105 indicated simply as an example.

I do not limit myself to the particular size, shape, number or arrangement of parts, as shown and described, all of which may be varied without going beyond the scope of 110

my invention as shown, described and claimed.

What I claim is:—

In a container, in combination, a receptacle, a transverse partition within the receptacle having an opening therein, a perforated sifter enclosing said opening and extending upwardly therefrom, means for opening and closing the perforations in the

sifter, a cover for the upper chamber having an opening considerably smaller than the cover and means for opening and closing the cover opening.

Signed at New York city, in the county of New York and State of New York, this 15 2nd day of June, 1921.

ESTELLE B. FINLAYSON.
